(57) **CLAIM**

We claim the ornamental design for a motor, as shown and described.

DESCRIPTION

FIG. 1 is a front perspective view of a motor of a first embodiment according to the present invention;

FIG. 2 is a rear perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof;

FIG. 8 is a bottom view thereof;

FIG. 9 is a cross-sectional view taken along the line 9-9 in FIG. 3;

FIG. 10 is an enlarged view of the area marked as 10 in FIG. 9;

FIG. 11 is a front perspective view of a motor of a second embodiment according to the present invention;

FIG. 12 is a rear perspective view thereof;

FIG. 13 is a front view thereof;

FIG. 14 is a rear view thereof;

FIG. 15 is a first side view thereof;

FIG. 16 is a second side view thereof;

FIG. 17 is a top view thereof;

FIG. 18 is a bottom view thereof;

FIG. 19 is a cross-sectional view taken along the line 19-19 in FIG. 13;

FIG. 20 is an end view of the sectioned part taken along the line 20-20 in FIG. 16;

FIG. 21 is an enlarged view of the area marked as 21 in FIG. 19; and,

FIG. 22 is an enlarged view of the area marked as 22 in FIG. 20.

The broken lines in the drawings represent portions of the motor that form no part of the claimed design.

1 Claim, 22 Drawing Sheets
